METHOD OF PRODUCING A GASEOUS MOTIVE FLUID WITH PULVERIZED FUEL

Walter Robinson and Bertrand A. Landry, Columbus, Ohio, assignors, by mesne assignments, to Allis-Chalmers Manufacturing Company, Milwaukee, Wis., a corporation of Delaware

Application February 9, 1946, Serial No. 646,542

7 Claims. (Cl. 60—39.02)

1

This invention relates generally to the combustion of pulverized fuel containing noncombustible solid material, and is directed toward and contemplates the production of large quantities of a heated high velocity motive fluid which is suitable for operating gas turbines and the like and which consists, at least in part, of products of combustion resulting from burning such fuel in suspension in a gaseous combustion supporting medium or carrier.

In this connection, a heretofore common conception is that if pulverized solid fuel, such as coal, is burned in suspension under conditions producing ash particles of small size, the erosiveness of the suspended ash particles will be so minimized as to render practical the formation and use of motive fluids as hereinabove indicated. And this conception has been confirmed by extensive experimentation in that it has been found that the erosive effect of suspended ash particles in general decreases as the size of the particles decrease and that the decrease in erosive effect is quite rapid as the size of the particles becomes less than 20 microns.

However, it has also been found that even if solid fuel is burned in suspension under conditions producing extremely small ash particles, the ash content of the resulting stream of motive fluid is relatively high and the erosive effect of the ash particles suspended therein is sufficiently great to render the life expectancy of turbine parts, particularly the blading, entirely too short for satisfactory commercial application. And although the quantity of suspended ash particles can be reduced through the use of suitable fly ash separators, it is extremely difficult and generally impracticable to thus reduce the quantity of small suspended ash particles sufficiently to increase the life expectancy of turbine parts to a satisfactory practical extent.

Another heretofore common and somewhat related conception is that if pulverized solid fuel is burned in suspension at a low temperature, the resulting ash particles will be sufficiently soft to render the erosiveness of such particles negligible.

However, extensive experimentation negatives the correctness of this conception in that even the small ash particles resulting from the low temperature combustion of pulverized solid fuel in suspension are in fact quite hard and have a jagged configuration which materially increases their erosive action on objects contacted thereby. In addition, the jagged configuration of the particles renders a mechanical separation of

5 same from the carrier gas stream particularly difficult as such particles present a relatively large surface area and consequently attain a velocity more nearly equal to that of the carrier fluid than do smooth ash particles of similar weight.

10 And therefore, the present invention is particularly concerned with and has as an object the production of a heated, high velocity motive fluid of the character mentioned hereinabove by burning pulverized fuel containing noncombustible solid material in a manner such that the noncombustible solid particles inherently present in suspension in the resulting stream of 15 combustion products are of a configuration conducive to minimizing the erosive effect of such particles and/or of a character best to enable a large portion of the particles to be readily removed from the carrier stream by passing the 20 stream through a conventional mechanical separator of simplified construction.

Another object of the present invention is to produce a heated, high velocity motive fluid, consisting at least in part of products of combustion, by burning pulverized fuel containing noncombustible solid matter in a manner effective to minimize the formation of lightweight and/or jagged ash particles.

Another object of the present invention is to produce a heated, high velocity motive fluid, 25 consisting at least in part of products of combustion, by burning pulverized fuel containing noncombustible solid material in a manner such that the noncombustible solid material inherently present in suspension in the resulting 30 stream of combustion products is in the form of particles preponderately of generally spheroidal shape.

An still another object of the present invention 35 is to produce a heated, high velocity motive fluid, consisting at least in part of products of combustion, by burning pulverized fuel containing noncombustible solid material in a manner such that the noncombustible solid material is present in suspension in the resulting stream of 40 combustion products in the form of particles preponderately of large size and generally spheroidal shape.

In accordance with this invention, one or 45 more of the hereinabove stated objects may be readily accomplished through the provision and operation of apparatus for burning pulverized solid fuel in suspension in a combustion supporting gaseous carrier under conditions producing a 50 high temperature zone through which the non-

combustible solid particles pass in confined suspension and become sufficiently fluid in passing therethrough to assume a generally spheroidal shape, and wherein movement of the fluid particles is preferably such as to cause such particles to collide and agglomerate and thereby form larger and heavier spheroidal particles before solidification occurs.

The manner of practicing the methods of the present invention will become readily apparent as the disclosure progresses and particularly points out, as hereinafter fully set forth, the various features, steps and advantages considered of special importance with respect to such methods. And in this connection, attention is directed to the following detailed description and appended claims, reference being had to the accompanying drawing illustrating one form of apparatus suitable for practicing the invention and in which:

Fig. 1 is a schematic showing of a simple continuous combustion gas turbine system embodying apparatus operable in accordance with this invention; and

Fig. 2 is an enlarged view of a modified flame and noncombustible particle confining structure illustrating the suspension and formation of particles of preferred shape and/or size.

Referring to the drawing, it will be seen that apparatus for use in connection with the practice of the present invention may include inner and outer concentrically arranged annular shells 1 and 2 forming therebetween an annular space 3 surrounding the combustion zone 4 defined by inner shell 1 and a pair of conduits 6 and 7 connecting zone 4 with suitable conventionally controllable sources of pulverized fuel and air (not shown). If desired, the interior of shell 1 may be provided with a suitable refractory lining 8 and with a converging discharge end portion 9, as shown in Fig. 2. The discharge end portions of conduits 6 and 7 may be arranged in concentric coaxial relation with respect to each other and with respect to the longitudinal axis of shell 1. And with such an arrangement of conduits, it is generally preferable to introduce the mixture of primary air and fuel (in this case pulverized coal suspended in an air stream) into zone 4 through conduit 6 and to introduce whatever additional air may be required in such zone in order to further control combustion and temperature conditions therein through conduit 7.

Cooling air may be controllably supplied to annular space 3 by means of a compressor 11 and a valve controlled conduit 12 connecting the discharge of compressor 11 with the interior of shell 2 at a point adjacent the closed or burner end thereof. Outer shell 2 extends a considerable distance longitudinally beyond the discharge end of shell 1 and provides a cooling zone 13 wherein the air issuing from annular space 3 mixes with and cools the combustion products issuing from zone 4 at a point adjacent the discharge end of shell 1. The discharge end of outer shell 2 is suitably connected with a conventional separator 14 which is in turn suitably connected, as by means of a conduit 16, with the inlet portion of a turbine 17 drivingly connected with the compressor 11. And a suitable starting motor 18 may be selectively drivingly connected with the compressor 11 and turbine 17 through a clutch or the like 19.

A gas turbine system of the type hereinabove

briefly described may be readily started and operated as heretofore known and when thus operated the coaction and functioning of the various elements of such a system are in general as follows: cooling air is delivered to annular space 3, a mixture of fuel and air is burned in zone 4 and perhaps to some extent in zone 13, air from space 3 and combustion products from zone 4 combine and mix in zone 13 to form a resulting motive fluid having a safe working temperature, and the resulting motive fluid passes through separator 14, wherein the heavier ash particles are removed from the fluid and then into turbine 17.

10. However, as hereinbefore pointed out the life expectancy of a turbine driven by motive fluid produced by the heretofore known methods of operating such systems with a fuel containing noncombustible solid material is entirely too short for satisfactory commercial application.

15. And in this connection it has been found that the ash content of the motive fluid thus produced is relatively high and that the ash particles present in such fluid are preponderately of lightweight and jagged configuration which is probably due to the fact that even if an ash fusing temperature is maintained in the combustion zone proper, the rate of travel of the combustion gases and therefore of the ash particles passing therethrough is so rapid that most of the ash particles do not become sufficiently fluid in passing through the combustion zone to attain a generally spheroidal shape before entering the cooling zone.

20. In accordance with applicants' method, the pulverized coal and air mixture introduced through conduit 6 and whatever additional air is introduced through conduit 7 are quantitatively adjusted so that despite the loss of heat to the air or

25. other gas in the surrounding annular space 3, the prevailing temperature in zone 4, particularly adjacent the discharge end thereof, is sufficiently high to fuse ash particles passing therethrough, and so that the turbulence and/or axial velocity

30. 35. of the combustion gases passing through zone 4 is sufficient to suspend and carry ash particles therethrough at a rate such that most of the particles become fluid and attain a generally spheroidal shape (see Fig. 2) before entering the cooling zone. And in this connection, it should be noted that when the shell or other structure defining zone 4 is shaped to form a converging discharge portion, as illustrated in Fig. 2, the

35. 40. 45. velocity and turbulence of the combustion gases and of the ash particles suspended therein will increase considerably in a manner materially increasing collisional agglomerations of the fluid particles passing through the discharge portion of the combustion zone. In addition to quantitatively adjusting the primary air and fuel mixture

50. 55. 60. and the secondary or additional combustion supporting air as above pointed out, the cooling air or gas delivered to annular space 3 is simultaneously quantitatively adjusted so that air leaving such space and mixing in zone 13 with the highly heated products of combustion leaving zone 4 will effect solidification of the fluid spheroids suspended in the combustion gases and will lower the temperature of such gases to a safe working value.

65. 70. 75. In practicing the present invention, it must be borne in mind that the prevailing temperature in zone 4 may be varied considerably depending upon the fusion temperature of the non-combustible solid particles or ash present in the

resulting stream of combustion gas. However, although the chemical composition of different particles of coal ash varies widely and consequently the fusion temperatures of such particles also vary widely, most coals have an ash fusion temperature of 2800° F., or less, and if the fuel and air delivered to zone 4 is quantitatively adjusted to produce therein a prevailing temperature of 2800° F., the ash of most coals will become sufficiently fluid to attain a spheroidal shape before leaving such zone, providing their rate of travel therethrough is not too rapid. The ash fusion temperatures of the commonly used coals can usually be obtained from the supplier, although if desired or considered necessary, the ash fusion characteristics of any coal can be readily determined by the standard American Society for Testing Materials method. And once the ash fusion temperature of the coal to be used is ascertained, all that has to be done in order to produce generally spheroidal ash particles is to quantitatively adjust the fuel and air delivered to zone 4 as hereinbefore indicated, bearing in mind of course, that the proportion of primary air and pulverized fuel used depends on the ignition characteristics of the coal and that the introduction of additional air into zone 4 is primarily for the purpose of completing combustion and regulating the temperature prevailing therein.

Motive fluid produced in accordance with this invention is far superior for the operation of turbines and the like than is motive fluid produced by the heretofore known methods of operation in that, as previously pointed out, spheroidal ash particles have less erosive effect on parts contacted thereby and can be more readily removed from a carrier gas stream than can jagged ash particles of similar weight produced by such known methods. And although the ash content of a motive fluid produced so as to contain ash particles preponderately of generally spheroidal form does, even if the ash particles are small and of light weight, materially prolong the life expectancy of turbines and the like operated thereby, the ash content of a motive fluid containing spheroidal ash particles can be further materially reduced by mechanical separation if the mass of the ash particles is increased by forming same under conditions producing collisional agglomerations thereof.

The present invention may be practiced with the aid of apparatus differing materially from that herein disclosed for purposes of illustration and the nature and character of the pulverized fuel and of the combustion supporting and cooling gas or gases employed may also differ and vary materially provided a heated, high velocity motive fluid, consisting at least in part of products of combustion, is produced by burning pulverized fuel containing noncombustible solid material under conditions such that the noncombustible solid material is present in suspension in the resulting stream of combustion products in the form of particles having a configuration minimizing the erosive effect of such particles on objects contacted thereby and/or of a character best to enable a large portion of the particles to be readily removed from the carrier stream by passing the stream through a separator of conventional construction. And it should therefore be understood that it is not intended to limit the present invention to the use of the particular apparatus, fuel and gases herein pointed out as being satisfactory for practicing same as various

modifications may occur to persons skilled in the art.

It is claimed and desired to secure by Letters Patent:

- 5 1. A method of producing large quantities of heated high velocity motive fluid including products of combustion formed by burning in a confined burning zone pulverized fuel containing noncombustible solid material in suspension in a combustion supporting carrier gas, said method comprising the transforming of said included noncombustible solid material into a particle form having a minimum erosive effect, by the steps of quantitatively regulating the fuel and gas introduced into said burning zone to create a temperature in said zone sufficiently high to cause the particles to fuse; then confining and directing said gas and fused particles in a cylindrical stream to create a gas flow condition effective to maintain said particles in suspension long enough to insure that most of said particles attain a generally spheroidal shape; and then at least downstream of said burning zone, surrounding said cylindrical stream with a stream of relatively cool gas to solidify said fused generally spheroidal particles.
- 10 2. A method of producing large quantities of heated high velocity motive fluid including products of combustion formed by burning in a confined burning zone pulverized fuel containing noncombustible solid material in suspension in a combustion supporting carrier gas, said method comprising the transforming of said included noncombustible solid material into a particle form having a minimum erosive effect and agglomerations of most of said particles that are of sufficient size to be easily removed from said motive fluid, by the steps of quantitatively regulating the fuel and gas introduced into said burning zone to create a temperature in said zone sufficiently high to cause the particles to fuse; then confining and directing said gas and fused particles in a cylindrical stream to create a gas flow condition effective to maintain said particles in suspension long enough to insure that most of said particles attain a generally spheroidal shape and collide to form agglomerations; and then at least downstream of said burning zone, surrounding said cylindrical stream with a stream of relatively cool gas to solidify said fused generally spheroidal particles and agglomerations.
- 15 3. A method of producing large quantities of heated high velocity motive fluid including products of combustion formed by burning in a confined burning zone pulverized fuel containing noncombustible solid material in suspension in a combustion supporting carrier gas, said method comprising the transforming of said included non-combustible solid material into a particle form having a minimum erosive effect and agglomerations of most of said particles that are of sufficient size so as to be easily removed from said motive fluid, by the steps of quantitatively regulating the fuel and gas introduced into said burning zone to create a temperature in said zone sufficiently high to cause the particles to fuse; then confining and directing said gas and fused particles in a cylindrical stream to create a gas flow condition effective to maintain said particles in suspension long enough to insure that most of said particles attain a generally spheroidal shape and collide to form agglomerations; and then at least downstream of said burning zone, surrounding said cylindrical stream with a stream of relatively cool gas directed in the same direction as

said cylindrical stream, to solidify said fused generally spheroidal particles and agglomerations.

4. A method of producing large quantities of heated high velocity motive fluid including products of combustion formed by burning in a confined burning zone pulverized fuel containing noncombustible solid material in suspension in a combustion supporting carrier gas, said method comprising the transforming of said included noncombustible solid material into a particle form having a minimum erosive effect, by the steps of quantitatively regulating the fuel and gas introduced into said burning zone to create a temperature in said zone sufficiently high to cause the particles to fuse; then confining and directing 15 said gas and fused particles in a cylindrical stream to create a gas flow condition effective to maintain said particles in suspension long enough to insure that most of said particles attain a generally spheroidal shape; and then at least downstream of said burning zone, surrounding said cylindrical stream with a stream of relatively cool gas directed in the same direction as said cylindrical stream, to solidify said fused generally spheroidal particles.

5. A method of producing large quantities of heated high velocity motive fluid including products of combustion formed by burning in a confined burning zone pulverized fuel containing noncombustible solid material in suspension in a combustion supporting carrier gas, said method comprising the transforming of said included noncombustible solid material into a particle form having a minimum erosive effect, by the steps of quantitatively regulating the fuel and gas introduced into said burning zone to create a temperature in said zone sufficiently high to cause the particles to fuse; then confining and directing 30 said gas and fused particles in a cylindrical stream to create a gas flow condition effective to maintain said particles in suspension long enough to insure that most of said particles attain a generally spheroidal shape; and then at least downstream of said burning zone, surrounding said cylindrical stream with a stream of relatively cool gas to mix with said cylindrical stream and solidify said fused generally spheroidal particles.

6. A method of producing large quantities of heated high velocity motive fluid including products of combustion formed by burning in a confined burning zone pulverized fuel containing noncombustible solid material in suspension in a combustion supporting carrier gas, said method comprising the transforming of said included noncombustible solid material into a particle form having a minimum erosive effect, by the steps of quantitatively regulating the fuel and gas intro-

duced into said burning zone to create a temperature in said zone sufficiently high to cause the particles to fuse; then confining and directing said gas and fused particles in a cylindrical stream to create a gas flow condition effective to maintain said particles in suspension long enough to insure that most of said particles attain a generally spheroidal shape; and then at least downstream of said burning zone, surrounding said cylindrical stream with a stream of relatively cool gas directed in the same direction as said cylindrical stream to mix therewith and solidify said fused generally spheroidal particles.

7. A method of producing large quantities of heated high velocity motive fluid including products of combustion formed by burning in a confined burning zone pulverized fuel containing noncombustible solid material in suspension in a combustion supporting carrier gas, the method comprising the transforming of said included noncombustible solid material into a particle form having a minimum erosive effect and agglomerations of most of said particles that are of sufficient size so as to be easily removed from said motive fluid, by the steps of quantitatively regulating the fuel and gas introduced into said burning zone to create a temperature in said zone sufficiently high to cause the particles to fuse; then confining and directing 25 said gas and fused particles in a cylindrical stream to create a gas flow condition effective to maintain said particles in suspension long enough to insure that most of said particles attain a generally spheroidal shape and collide to form agglomerations; and then at least downstream of said burning zone, surrounding said cylindrical stream with a stream of relatively cool gas to mix with said cylindrical stream and solidify said fused generally spheroidal particles and agglomerations.
